UNITED STATES PATENT OFFICE.

HERMAN DOERING, OF REEDSBURG, WISCONSIN.

STITCHING-HORSE.

SPECIFICATION forming part of Letters Patent No. 378,295, dated February 21, 1882.

Application filed December 21, 1887. Serial No. 258,562. (No model.)

To all whom it may concern:

Be it known that I, HERMAN DOERING, a citizen of the United States, residing at Reedsburg, in the county of Sauk and State of Wisconsin, have invented certain new and useful Improvements in Stitching-Horses, of which the following is a full and clear description, reference being had to the accompanying drawings, forming part of this specification, in which—

Figure 1 represents a perspective view of a stitching-horse embodying my invention. Fig. 2 is an elevation, partly in section, showing one of the side plates removed. Fig. 3 is a detail of the casting L.

My invention relates to that class of machines for stitching leather articles—such as harness—and commonly known to the trade as "stitching-horses;" and my invention consists in the improved constructions and combinations of devices which I shall hereinafter fully describe and claim.

To enable others skilled in the art to make and use my invention, I will now describe the same and indicate the manner in which the same is carried out.

In the said drawings, A represents a suitable frame, comprising the supporting legs a, the seat b, and the rock-shaft c. The seat portion b is provided with a curved recess, d, in the center of which an opening, e, is formed, and on the upper surface of said seat, contiguous to the recess d, are secured castings f, having horizontal arms, by which they are secured to said seat, and vertical arms g, through which bolts are passed.

In shoulders e', formed in the seat on each side of the recess d, are vertically-arranged side pieces, B, having slotted lower ends, through which the bolts h pass to secure said side pieces, and to permit their vertical adjustment to increase or lessen the height of the machine.

The jaws C, between the faces of which the leather or other material to be sewed is placed, are provided with inwardly-extending lugs i, through which and the upper ends of the side pieces, B, a bolt, D, is passed, thereby forming a hinge-connection for said jaws, said bolt being threaded and serving to draw the side pieces firmly together against the lower por-

tions of the jaws. The jaws C are also provided with downwardly-extending short arms C', and to these arms the upper ends of levers E E' are hinged or otherwise pivotally connected. 55 These levers extend in opposite directions and are acted upon by a spring, F, coiled around a bar, k, between the side pieces, B, having one end bearing against one of the levers E and its opposite ends secured in the opposite lever, E'.

The lever E' is formed with two parallel long arms, m, and the lever E is provided with a single long arm, n, which passes between the arms of the opposite lever, while the lower 65 ends of both levers are attached to a strap or connection, G, which passes therefrom through openings b' in the ends of the recess b, and is connected with a foot-lever, H, pivoted to the rock-shaft c, and provided with a pawl, o, 70 adapted to engage a rack, p, secured to one of the legs a.

Just below the jointed connection with the jaws C the levers are provided with inwardly-extending lugs l, through which a bolt, r, is 75 passed to form a hinge, whereby the upper ends of the levers E E' are held together. The bolt which passes through these lugs l also projects into elongated slots s in the upper portions of the side pieces and plays loosely therein, 80 to provide for the necessary movement of the upper or short arms of said levers.

In each end of the recess b, contiguous to the openings b', is secured a bracket, L, having upwardly-extending lugs t, between which a 85 roller, u, is loosely mounted, and over these rollers the strap G passes after leaving the end of the levers E E'. It will thus be seen that upon depressing the foot-lever H the strap or connection draws the lower ends of the levers 90 E E' outward and causes the upper or short arms of said levers to force the lower short arms, C', of the jaws C outward, thereby closing the gripping-faces of said jaws tightly against the material or article to be operated 95 upon. After the jaws are closed the foot-lever H is moved laterally, so that its pawl will engage the rack p, and thereby hold the several parts in a closed position.

To release the article or material between the jaws, the operator simply moves the foot-lever out of its engagement with the rack, when

the spring F, acting upon the long arms of the levers E E', causes the gripping-faces of the jaws to separate by a movement the reverse of that just described.

5 Having thus described my invention, what I claim as new, and desire to secure by Letters Patent, is—

1. The combination, with the frame A, provided with the seat-frame, the operating foot-lever, and the rock-shaft, of the vertically-adjustable side pieces, the crossed levers pivoted together between said side pieces, the jaws C, pivoted together and to the short arms of the levers, and a strap or connection between the lower ends of the levers and the operating foot-lever, substantially as described.

2. The frame A, having the recessed seat portion, the foot-lever, and the rock-shaft, in combination with the slotted side pieces, the 20 lugs and bolts by which they are vertically adjusted, the levers E E', pivoted together and

moving in opposite directions, a spring acting upon the long arms of said levers, the jaws pivoted together and having their short arms pivoted or hinged to the short arms of the levers, and the strap-connection between the levers and foot-lever, and a holding pawl and rack for the lever, substantially as described.

3. The seat portion having the recess and opening, the adjustable and slotted side pieces, the pivoted crossed levers, and the pivoted spring-actuated gripping jaws hinged thereto, in combination with the brackets L, the rollers mounted therein, and the strap connected with the long arms of the levers, passing over 30 said rollers and through openings in the seat portion and connected with the foot-lever, substantially as described.

HERMAN DOERING.
